SEWING MACHINE

Charles F. Rubel, Chicago, Ill., assignor to Union
Special Machine Company, Chicago, Ill., a cor-
poration of Illinois

Application February 3, 1934, Serial No. 709,645

9 Claims. (Cl. 112—215)

The invention relates to new and useful im-
provements in sewing machines, and more par-
ticularly to the driving mechanism for the main
actuating shaft and the devices operated thereby
5 for actuating the feed.

An object of the invention is to provide a sewing
machine wherein the main actuating shaft
is driven by a connection thereto intermediate the
ends thereof, and wherein the feed dog is actuated
10 for feeding the fabric by a driving connec-
tion at the end of said actuating shaft.

A further object of the invention is to pro-
vide a machine of the above type wherein the
feed dog is moved back and forth for imparting
15 a feeding movement to the fabric by a crank
which is adjustably mounted on a disk carried at
the end of the actuating shaft.

A still further object of the invention is to pro-
vide a machine of the above type with a feeding
20 mechanism wherein the feed bar carrying the feed
dog is moved endwise through a connection with
the rocker oscillated by an actuating crank at
the end of the main actuating shaft, and wherein
the feed bar is raised and lowered by an oscillat-
25 ing lever connected to the feed bar by a link and
given its oscillations by an eccentric strap co-
operating with an eccentric on the main actuating
shaft.

These and other objects will in part be obvious
30 and will in part be hereinafter more fully de-
scribed.

In the drawings—

Figure 1 is a plan view of the machine embody-
ing the improvements;

Fig. 2 is a side view of the machine with parts
35 broken away and parts in section to show more
particularly the mechanism for operating the feed
dog;

Fig. 3 is a sectional view on the line 3—3 of
40 Fig. 2;

Fig. 4 is a view showing more or less diagram-
matically and in side elevation, the means for
45 oscillating the feed rocker;

Fig. 5 is a view from the rear of the machine
45 showing the end of the actuating shaft, the feed
rocker and the means for imparting oscillations
to the feed rocker from said actuating shaft;

Fig. 6 is a plan view partly in section showing
50 the actuating arm for raising and lowering the
feed bar, and

Fig. 7 is a sectional view showing the manner of
adjusting the feed actuating crank.

The invention is shown as applied to a machine
of the type disclosed in the patent granted Nor-
55 man V. Christensen and Frederick F. Zeier, March

25, 1930, No. 1,751,508. In this machine, the main
actuating shaft is located above the work sup-
port and extends in the general direction of the
line of feed. It is offset slightly to the line of
feed, and is disposed in a plane which is inclined
5 to said line of feed. The fabric is moved across
the work support by a feeding mechanism which
includes a feed dog carried by a feed bar. The
present invention has particularly to do with the
means whereby the main actuating shaft located
10 in the standard above the work support is op-
erated and the devices which are actuated by said
shaft for imparting feeding movements to the
feed dog. The main actuating shaft is operated
from a driving pulley located at the side of the
15 standard and the actuating shaft. This pulley is
carried by a short shaft which is provided with
a bevel gear meshing with a bevel gear located
on the actuating shaft intermediate the ends
thereof. This leaves the ends of the main actuat-
20 ing shaft free. The rear end of the actuating
shaft is provided with a disk carrying a crank
which is adjustable in a radial slot therein, and
this crank actuates the link which is connected
to an arm carried by the feed rocker, and the
25 feed bar is pivotally attached to this feed rocker;
thus it is that the feed bar is moved back and
forth. Mounted on the fulcrum shaft for the
feed rocker is a lever which swings independently
30 of the feed rocker. This lever is connected at its
outer end to a link which is attached at its upper
end to the feed bar. The lever is raised
and lowered by an eccentric strap which has a
35 direct connection thereto, and this eccentric strap
cooperates with an eccentric on the main actuat-
ing shaft. This provides a very efficient actuating
means for the feed dog which is capable of
40 handling heavy materials where the strain in-
cident to the clamping of the material and the
moving of the same is much greater than the
normal strains imposed upon the feed dog in ordi-
nary stitching. Furthermore, the feeding mecha-
45 nism is such as to enable the feed dog to be given
a relatively long stroke and thus long stitches
produced.

Referring more in detail to the drawings, the
invention is shown as applied to a sewing machine
which includes a supporting bed 1. Said support-
ing bed 1 is provided with suitable supporting
members on which a work support 2 is rigidly
50 mounted. Mounted on the bed and extending up-
wardly therefrom is a standard 3 which is pro-
vided with bearings, and the main actuating shaft
4 is mounted for rotation in the bearings carried
55 by this standard. This main actuating shaft 4 is

located above the work support 2. Said shaft inclines downwardly relative to the plane of the work support, and as clearly shown in Fig. 1, the shaft also is disposed in a vertical plane which is 5 inclined to the line of feed.

The machine includes a needle bar 5 carrying a needle 6, and cooperating with the needle 6 beneath the work support is a looper 7. The looper 7 is mounted on a looper carrier 8 which is oscillated by suitable connections with an eccentric strap 9. The looper is given its needle avoiding movements by means of an arm 10 which carries a ball stud to which an eccentric strap 11 is connected. The stitch forming mechanism forms 10 no part of the present invention.

The material is held on the work support 3 by a presser foot 12 and is fed across the work support to the stitching mechanism by means of a feed dog 13. The feed dog 13 is carried by a feed bar 14. 20 Said feed dog is provided with a shank 15 which is slotted, and a screw 16 passing through the slot rigidly clamps the feed dog to the feed bar. The feed bar at its rear end is fixed to a pin 17 and the pin 17 is journaled in the arms 18, 18 carried 25 at the upper end of the feed rocker 19. The feed rocker 19 is provided with arms 20, 20 which are journaled on a fixed shaft 23a mounted at one end in the standard 3, and mounted at the other end in a supporting member carried by the bed and carrying the work support.

The feed rocker is oscillated by a plate 21 which is fixed thereto and carries a rearwardly projecting arm 22. Said plate is attached to the feed rocker by suitable screws 23, 23 one of which is 30 shown in Fig. 5. At the outer end of said arm 22 is a ball stud 24. A link 25 is connected to the ball stud. On the rear end of the main actuating shaft 4 is a disk 26 which is fixed thereto by set screws 27, 27. This disk is provided with a 35 radial slot, and mounted in said radial slot is a crank pin 29. The radial slot is T-shaped in cross section, and the crank pin has a T-shaped head which slides therein. Carried by the crank pin is 40 a sleeve provided with a ball and the link 25 en-

the inner end, said lever is connected to a link 37. Said link is forked at its lower end, and the end of the lever extends into the fork, and the pivot pin 38 joins the link to the lever. The upper end of the link is likewise forked and the feed bar 14 lies in said fork and is secured to the link by a pivot pin 39. Attached to this lever 35 is a stud 40 carrying a ball with which an eccentric strap 41 is attached. The eccentric strap 41 cooperates with an eccentric 42 on the main actuating shaft 4. As the main actuating shaft rotates, it will impart endwise movement to this eccentric strap 41, and this will in turn oscillate the lever, raising and lowering the inner end thereof. This movement imparted to the lever 35 will give an 15 endwise movement to the link 37 which will raise and lower the feed bar.

From the above it will be apparent that a driving means for the main actuating shaft has been provided which is connected thereto intermediate 20 the ends of the actuating shaft. The feed dog derives its movements from actuated parts directly connected to this actuating shaft. The feed rocker which gives fabric feeding movements to the feed dog is oscillated by a crank pin at the 25 rear end of the shaft, and the lever which raises and lowers the feed dog is actuated by an eccentric strap which is directly connected thereto and which cooperates with an eccentric on the actuating shaft disposed intermediate the ends thereof. This provides a very efficient and simple feeding mechanism which is especially adapted for 30 heavy work, and for producing relatively long stitches. The crank pin carried by the disk may be adjusted through a wide range and a sufficient throw obtained for the longest stitch desired. As 35 a means for lubricating the gears through which the main actuating shaft is rotated, a housing 43 is provided which completely houses said gears, and this housing may be supplied with a lubricating oil so that the gears will run in oil.

It is obvious that minor changes in the details of construction may be made without departing from the spirit of the invention as set forth in the

3. In a sewing machine, a work support, a main actuating shaft located above the work support, driving means for said main actuating shaft connected thereto intermediate the ends thereof, a feed bar, means for imparting endwise movement to said feed bar including a feed rocker to which said feed bar is attached, a disk carried by the rear end of said main actuating shaft, a crank pin mounted for radial adjustment on said disk, a ball stud carried thereby, an arm projecting rearwardly from the feed rocker, a ball stud carried thereby, a link connecting said ball studs, a lever mounted beneath the feed bar for oscillations in a vertical plane, a link connecting the free end of said lever with the free end of said feed bar, an eccentric on said main actuating shaft, an eccentric strap cooperating therewith, and a ball stud carried by said lever to which said eccentric strap is attached.
- 10 4. In a sewing machine, a work support, a main actuating shaft located above the work support, a feed bar, means operated by said main actuating shaft for imparting endwise movement to the feed bar, a lever mounted beneath the feed bar for movement in a vertical plane, a link connecting the free end of said lever to the free end of the feed bar, an eccentric strap cooperating with an eccentric on the main actuating shaft, and a ball stud carried by said lever to which said eccentric strap is connected.
- 15 5. In a sewing machine, a work support, a main actuating shaft located above the work support, driving means for said main actuating shaft connected thereto intermediate the ends thereof, a feed bar, means for imparting endwise movement to the feed bar including a feed rocker to which said feed bar is pivoted, a plate secured to the feed rocker and having an arm projecting rearwardly therefrom, a ball stud carried by said arm, a disk on the rear end of said actuating shaft, a crank pin mounted for radial adjustment on said disk, and a link connecting said crank pin to said ball stud for oscillating said feed rocker.
- 20 6. In a sewing machine, a work support, a main actuating shaft located above the work support, driving means for said main actuating shaft connected thereto intermediate the ends thereof, a feed bar, means for imparting endwise movement to the feed bar including a feed rocker to which said feed bar is pivoted, a plate secured to the feed rocker and having an arm projecting rearwardly therefrom, a ball stud carried by said arm, a disk on the rear end of said actuating shaft, a crank pin mounted for radial adjustment on said disk, a link connecting said crank pin to said ball stud for oscillating said feed rocker.
- 25 7. In a sewing machine, a work support, a main actuating shaft located above the work support, a feed bar, means for imparting endwise movement to the feed bar including a feed rocker to which said feed bar is pivoted, a plate secured to the feed rocker and having an arm projecting rearwardly therefrom, a ball stud carried by said arm, a disk on the rear end of said actuating shaft, a crank pin mounted for radial adjustment on said disk, a link connecting said crank pin to said ball stud for oscillating said feed rocker, means for clamping said crank pin in a fixed position on said disk, and means for shifting said crank pin when released to different set positions.
- 30 8. In a sewing machine, a work support, a main actuating shaft located above the work support, a feed bar, a feed rocker to which said feed bar is pivotally connected, means for oscillating said feed rocker from said main actuating shaft, a stationary shaft on which said feed rocker is mounted for oscillation, a lever mounted on said stationary shaft for oscillation in a vertical plane independently of said feed rocker, a link pivoted to the free end of said lever and pivoted to the free end of said feed bar, said link being disposed in substantially a vertical position, a ball stud carried by said lever, an eccentric on said main actuating shaft, and an eccentric strap cooperating with said eccentric and connected to said ball stud for oscillating said lever.
- 35 9. In a sewing machine, a work support, a main actuating shaft located above the work support, an operating shaft disposed at right angles to the main actuating shaft and geared to said main actuating shaft intermediate the ends thereof, a feed dog, a feed bar supporting said feed dog, means for imparting endwise movement to said feed bar including a crank pin adjustably mounted at the rear end of said main actuating shaft, means for raising and lowering said feed bar including an eccentric strap cooperating with an eccentric on said main actuating shaft, and devices connecting said eccentric strap to said feed bar adjacent the free end thereof.
